UNITED STATES PATENT OFFICE.

HENRY F. CRIM AND WILLIAM C. LOY, OF ROCHESTER, INDIANA.

PERMUTATION-PADLOCK.

No. 904,182.

Specification of Letters Patent.

Patented Nov. 17, 1908.

Application filed February 17, 1908. Serial No. 416,372.

To all whom it may concern:

Be it known that we, HENRY F. CRIM and WILLIAM C. LOY, citizens of the United States, residing at Rochester, in the county 5 of Fulton and State of Indiana, have invented certain new and useful Improvements in Permutation-Padlocks; and we do declare the following to be a full, clear, and exact description of the invention, such as 10 will enable others skilled in the art to which it appertains to make and use the same, reference being had to the accompanying drawings, and to the letters and figures of reference marked thereon, which form a part of 15 this specification.

Our invention relates to locks, but more particularly to a permutation pad-lock, and has for its object to provide a device of this class which is particularly simple in its construction, cheap to manufacture, strong and durable.

A further object of our invention is to provide certain improvements over our pending application Serial No. 354,952, filed January 30, 1907, patented Feb. 18, 25 1908, No. 879,747.

A further object of our invention is to provide a permutation pad-lock, the interior and working parts of which are readily accessible when the shackle is in an unlocked position, in such manner that the combination of the lock can be readily changed at any time, and this is accomplished without the use of tools or instruments and without 35 disfiguring the lock in any way.

A further object of our invention is to provide a permutation pad-lock having an improved dial which is so constructed that the lock can be opened in the dark or by a 40 person blind.

With these objects in view our invention consists in the combination of the lock, casing, shackle, tumblers and cap; and our invention also consists in the construction of 45 the dial, all of which will be first fully described and afterwards specifically pointed out in the appended claims.

Referring to the accompanying drawing. Figure 1 is an elevation of the lock showing 50 the dial. Fig. 2 is a vertical sectional view taken through the lock and casing. Fig. 3 is a plan view of the casing with cap removed. Fig. 4 is a plan view of the lock. Fig. 5 is a perspective view of the cap. Fig. 55 6 is a plan view of the three tumblers, and

Fig. 7 is a plan of one of the separating washers.

Like numerals of reference indicate the same parts throughout the several figures in which:

1 indicates the permutation pad-lock comprising the body or casing 2, said body or casing being provided with an extension 3 to which the shackle 4 is pivoted at 5. Except for the extension 3 it will be seen that 65 the body or casing 2 is circular, and by referring to Figs. 2 and 3 it will be seen that the said body 2 is recessed at 6 to accommodate the circular tumblers 7, 8 and 9, the annular wall 10, face 11 and extension 3 being integral and preferably formed out of a 70 solid piece of metal. Upon the face 11, as shown in Fig. 1, is formed a dial 12, said dial being provided with a series of raised numbers 13 ranging from one to ten or more, 75 and around the edge of said dial we provide a raised rim 14 as shown in Fig. 2, said rim 14 being provided with a series of notches 15, said notches being disposed at regular intervals to agree with the numbers on the 80 dial, and intermediate notches between the numbers on the dial as clearly shown in Fig. 1. We prefer to make one of the notches larger or deeper as shown at 16 (Fig. 1) which notch will indicate the starting 85 point for the pointer 17, and we provide the end of the pointer 17 with an extension 18 to enter the said notches 15 as shown in Fig. 2 so that the pointer 17 will pass over the rim 14 and drop into the notches 15 as 90 is apparent.

19 indicates the shaft or spindle upon which the pointer 17 is carried, and 20 indicates a turn button secured to said shaft or to said pointer as shown in Figs. 1 and 95 2, by means of which turn button the pointer 17 is moved over the face of the dial.

Secured to the shaft or spindle 19 or formed integral therewith and on the inside of the casing is a disk 21, said disk being 100 provided around its periphery with a series of notches 22 as shown in Fig. 3.

Referring to Fig. 6 which illustrates the circular tumblers, it will be seen that the tumbler 7 is provided with a lug 23 on its 105 upper face and a similar lug 24 on its lower face, said lug 24 being shown in dotted lines. The tumbler 8 is also provided with an upper and a lower lug 25 and 26, while the tumbler 9 is provided only with a lower lug 110

27. It will also be seen from Fig. 6 that a portion of the periphery of each of the tumblers is cut away forming in each tumbler a recess 28, and in this connection it will 5 be seen from Fig. 3 that the wall 10 of the casing is similarly cut away or recessed at 29, the notches 28 in the tumblers forming substantially a circular opening when registering with the recess 29 in the wall 10 of 10 the casing.

30 indicates the cap or top of the lock which, as shown in Figs. 2 and 5, is provided with a flange or wall 31, said flange or wall being provided with preferably two oppositely disposed transverse slots 32 which terminate in oppositely disposed longitudinal slots 33 as shown in Fig. 5; while the wall 10 of the casing is provided with two oppositely disposed lugs 34 arranged to enter 15 the transverse slots 32 in the flange or wall 31 of the cap 30. A central tube 35 carried on the cap 30 accommodates two of the circular tumblers 8 and 9 as shown in Fig. 2; while the lower tumbler 7 is mounted on the 20 shaft or spindle 19, the lug 24 on said tumbler entering one of the notches 22 in the disk 21 in such manner that said tumbler 7 rotates with the disk 21.

Referring now to Fig. 4 it will be seen 30 that the cap 30 is cut away or recessed at 36 allowing the end 37 of the shackle 4 to enter the lock as shown in Fig. 2, said end 37 of the shackle being provided with three transverse grooves 38 within which the tumblers 35 7, 8 and 9 enter as shown in Fig. 2.

Referring now to Figs. 2, 5 and 7 it will be seen that the central tube 35 on the cap 30 is provided with a longitudinal slot 39, while the washers 40 which are disposed 40 on the central tube 35 are each provided with an extension or tongue 41 which enters the slot 39 in the tube 35 allowing said washers to be moved slidably but not rotatably on said tube 35. By this construction the said washers 40 are not rotated by 45 the tumblers 7, 8 and 9.

Having thus fully described our invention its operation is as follows: The parts having been assembled the circular tumblers 7, 8 and 50 9 are rotated by means of the turn button 20 associated with the pointer 17, and any movement imparted to the turn button 20 rotates the disk 21 on the inside of the lock, and as the lower tumbler 7 is in interlocking 55 engagement with said disk said lower tumbler 7 is necessarily rotated with said disk 21. The central or intermediate tumbler 8 having its lower lug 26 directly in the path of the upper lug 23 on the tumbler 7 said 60 tumbler 8 is rotated when the lugs 23 and 26 come into engagement. The central tumbler 8 being provided with an upper lug 25 and the tumbler 9 being provided with a lower lug 27 and said lugs being in the same 65 path the said tumbler 9 is rotated by the

tumbler 8 when the said lugs 25 and 27 come into engagement.

In order to unlock the lock or release the shackle 4 from engagement with the tumblers it is necessary that every one of the 70 notches or recesses 28 in the tumblers 7, 8 and 9 register one above the other and at the same time register with the notch or recess 29 in the wall 10 of the casing, and unless these tumblers are brought into this 75 position one or more of them will be in engagement with the shackle and thereby hold the same in a locked position. The tumblers are placed within the lock so that the pointer 17 will have to be rotated to a 80 certain point and back to a certain point and again forward to a certain point in order to bring the notches in all of the tumblers directly in line and register with the notch or recess 29 in the wall 10 of the casing; consequently the lock can be opened at 85 any time when the combination is known. By the construction of the dial 12 the extent of movement of the pointer over the face of the dial can be determined by the sense of 90 touch, for the reason that the numbers being raised they can be determined by touch, and as the end of the pointer enters the notches 15 in the raised rim 14 of the dial the extent of movement of the pointer can 95 be counted by the number of notches in which it enters. As for example, if the 8th notch from the starting notch was directly opposite the numeral four and it was necessary to rotate the pointer to the numeral 100 four in order to effect the first movement of the combination the sounds of the pointer passing into the notches successively can be counted and eight of them will bring the pointer to the numeral four. The pointer 105 must now be moved in the opposite direction and if the number of notches be known the pointer can be moved to the exact position and then moved back again in the opposite direction, constituting the last movement required for the combination. By this construction it is apparent that the lock can be 110 opened in the dark or by a person blind as well as if the dial were in plain view.

It will be seen from the drawings that 115 access can be had to the interior of the lock only by removing the cap or top 30, and it will also be seen, particularly from Figs. 2 and 4 that the said top or cap cannot be removed while the shackle is in a locked position, as the said shackle passes through a portion of the top or cap 30 and securely locks said top or cap against rotation. This will be evident from Fig. 4 which shows the recess 36 in the cap 30 in dotted lines in one 120 position and in full lines in its normal position. When the lugs 34 on the wall 10 are passing into the transverse slots 32 on the wall or flange 31 of the cap 30 the recess 36 through which the shackle passes is in posi- 125 130

tion shown in dotted lines in Fig. 4; and when the lugs 34 on the wall 10 reach the longitudinal slots 33 in the wall or flange 31 the cap 30 is slightly rotated by carrying 5 the recess 36 into position shown in full lines in Fig. 4 and causes said lugs 34 to pass into the longitudinal slots 33 in the wall or flange 31, thus securely locking the cap 30 in position. Since it is necessary 10 therefore to rotate the cap 30 into position shown in dotted lines in Fig. 4 in order to remove said cap or top it is clearly evident that this rotation cannot be effected while the shackle 4 is in position shown in Fig. 15 2; thus the shackle securely locks the top or cap in position and absolutely prevents all access to the interior of the lock.

In order to change or alter the combination of the lock the cap 30 and tumblers are 20 removed and the last tumbler 7 rotated so that its lower lug will enter a different notch 22 in the disk 21 (Fig. 3). This of course alters the position of the notch 28 on the disk 7 with relation to the pointer 17 on the 25 dial 12, thereby changing the combination.

Having thus fully described our invention what we claim as new and desire to secure by Letters Patent of the United States is:

1. In a permutation pad-lock of the character described, the combination of a casing 30 comprising the annular wall 10, face 11, and extension 3, a shackle 4 pivoted to said extension, a series of tumblers within said casing for engagement with the free end of 35 the shackle, a cap 30 for said casing, said cap being cut away on its periphery to receive said shackle, a wall or flange formed on said cap, said wall or flange being provided with a transverse slot and a longitudinal slot 40 communicating with said transverse slot, a lug 34 on the said annular wall 10 arranged to enter said transverse slot and said longitudinal slot, the said annular wall 10 being provided with a recess 29 and the 45 said tumblers being each provided with a notch 28 on its periphery to register with the said recess 29 in the annular wall 10, the said free end of the shackle entering said recess 29 in the wall 10 and said notches 28 50 in the peripheries of the tumblers, substantially as described.

2. In a permutation pad-lock of the character described, the combination of a casing comprising an annular wall, a face and an 55 extension, a shackle pivoted to said exten-

sion, a series of tumblers within said casing for engagement with the free end of said shackle, a cap for said casing, a slotted wall or flange on said cap and a central tube on said cap, a lug on the annular wall of said 60 casing for interlocking engagement with the flange or wall on said cap, said cap being cut away on its periphery to receive said shackle, the said annular wall being provided with a recess and said tumblers being each provided 65 with a notch in its periphery to register with the said recess in the said annular wall, said central tube on said cap being provided with a longitudinal slot, washers each having a tongue or extension thereon disposed 70 on said central tube, said tongue or extension entering the said longitudinal slot in said central tube to prevent rotation of each of said washers, the said free end of the shackle entering the said recess in the annular wall of the casing and entering said 75 notches in the peripheries of the tumblers, substantially as described.

3. In a permutation lock of the character described, the combination of a casing comprising an annular wall, a face and an extension, a shackle pivoted to said extension, a dial formed on said face, said dial comprising a series of raised numerals or symbols, and an outer rim, said outer rim being provided with a series of notches and a notch 80 distinguishable from said series of notches, a pointer on said dial constructed to engage said outer rim and enter the said notches therein, a series of tumblers within the 85 casing, and a cap for said casing, said tumblers being arranged to engage the free end of said shackle to lock the same, and means for rotating said tumblers to carry the same out of engagement with the free end of the 90 shackle, the whole being arranged in such manner that the extent of movement of the said pointer on said dial can be determined by the sound of the said pointer entering the 95 notches in the outer rim and also determined by the raised numerals or symbols on the 100 said dial by sense of touch, substantially as described.

In testimony whereof, we affix our signatures, in presence of two witnesses.
